CLAIM

The ornamental design for fold down wheels for carpet cleaner, as shown and described.

DESCRIPTION

FIG. 1 is a right side elevational view of the fold down wheels for carpet cleaner showing my new design, the broken lines are for illustrative purposes only and form no part of the claimed design;

FIG. 2 is a front elevational view thereof;

FIG. 3 is a left side elevational view thereof;

FIG. 4 is a top plan view thereof;

FIG. 5 is a bottom plan view thereof;

FIG. 6 is a rear elevational view thereof.
